UNITED STATES PATENT OFFICE.

NELSON S. BURTON, OF ARDMORE, OKLAHOMA.

ROTARY WELL DRILL.

Application filed May 8, 1924. Serial No. 711,874.

To all whom it may concern:

Be it known that I, NELSON S. BURTON, a citizen of the United States, residing at Ardmore, in the county of Carter and State 5 of Oklahoma, have invented certain new and useful Improvements in Rotary Well Drills, of which the following is a specification, reference being had to the accompanying drawings.

- 10 This invention relates to rotary well drilling apparatus and more particularly to that type of drilling apparatus in which a drill of less size than the bore desired is employed and the drill pipe has arranged thereon 15 above the drill a reamer for enlarging the bore. This type of drilling apparatus is employed in difficult formations for the reason that it is particularly adapted for the production of straight bores in such formation. 20 An important object of this invention is to provide an improved construction and mounting for the reamer embodying means whereby circulation of water may be properly fed to the blades of the reamer and 25 whereby the reamer is conveniently supported at a point spaced above the last joint of the tool line, permitting this jointed tool line to be operating in an opening slightly larger than the joint so that it will be maintained 30 in alignment and guide the reamer properly in the formation of the larger or casing receiving bore.

These and other objects I attain by the construction shown in the accompanying 35 drawings, wherein for the purpose of illustration is shown a preferred embodiment of my invention and wherein:—

Figure 1 is a side elevation showing a 40 reamer constructed in accordance with my invention;

Figure 1^a is a reduced side view showing the entire drilling assemblage;

Figure 2 is a view similar to that shown in 45 Figure 1 but taken at right angles thereto;

Figure 3 is a vertical sectional view through the reamer;

Figure 4 is a section through the upper end of the reamer;

Figure 5 is a section taken approximately 50 midway between the ends of the reamer.

Referring now, more particularly to the drawings, the lower end of the drill pipe is provided with an enlarged double pin tool joint 10, the larger or upper pin 11 thereof

55 fitting the box at the upper end of a sleeve 12, while the lower or smaller pin 13 thereof

fits the shank of a double box tool joint 14 which is of the usual construction with the exception of the fact that it is made somewhat longer than those ordinarily employed. 60

This tool joint 10 has a central bore 15 which is in communication through downwardly inclining ports 16 with the outer surface of the sleeve immediately in advance of vertical reamer blades 17 formed upon the 65 sleeve. This bore 15 is also in communication with further ports 18 which communicate with longitudinally extending ports 19 of the sleeve which open through the bottom of the sleeve immediately in advance of the 70 lower ends of these blades which are continued below the under end of the sleeve and have extensions 20 underlying and jointed to the sleeve. The rear faces of these blades at their lower ends will be beveled, as at 21, 75 in the usual manner and the blades are preferably provided upon their outer surface with the usual decrease in thickness for the purpose of providing clearance.

It is seen that when a reamer of this type 80 is in position within the bore two depths of water will be applied to the front face of the reamer blades, one to the front edge of the blade adjacent the upper end thereof and directed downwardly along this edge and the other opening directly to the cutting portion proper of the blade at the lower end thereof. By this arrangement proper cooling of the 85 blades and removal therefrom of sticky sediment is assured.

The sleeve 12 has a bore 23 snugly receiving the drill joint 14 so that proper alignment of the sleeve and drill joint are obtained. The lower end of this drill joint will preferably have applied thereto a fish tail 90 bit 24 of any desired construction. This tool joint has, of course, the usual central water course 25 communicating with the water ports of the fish tail bit. It will be obvious that when it is necessary to sharpen either 95 the blades of the reamer or the fish tail bit, it may be accomplished by withdrawing the drill pipe and removing the tool which it is desired to employ. In the construction of the joint 25 care is taken that the wrench square 26 thereof is disposed beneath the lower end of the reamer so that it is readily accessible for removal as a unit with the fish tail bit or for holding while the fish tail bit 100 is removed.

Many changes and modifications of the 105 structure hereinbefore recited being possible

without materially departing from the spirit of my invention, I do not limit myself to such specific structure as hereinbefore set forth except as hereinafter claimed.

5. I claim:

1. In well drilling apparatus and in combination, a tool joint having a double pin at its lower end, a drill joint engaging the smaller pin of the tool joint, a sleeve engaging the larger pin of the tool joint, a bit engaged with the lower end of the drill joint, and reamer blades formed on the outer surface of the sleeve.
- 10 2. In well drilling apparatus and in combination, a tool joint having a double pin at its lower end, a drill joint engaging the smaller pin of the tool joint, a sleeve engaging the larger pin of the tool joint, a bit engaged with the lower end of the drill joint, and reamer blades formed on the outer surface of the sleeve, said tool joint having a longitudinal water port, the drill joint having a similar port communicating with the water port of the tool joint, the sleeve having longitudinally extending ports for delivering fluid to said reamer blades, the ports of the sleeve communicating through the wall of the pin engaged by the sleeve with the port of said tool joint.
- 15 3. In combination with a drill pipe including a tool joint disposed of above the lower end thereof and having a pin, a reamer comprising a sleeve surrounding the drill pipe, and having a box at its upper end for engagement with the pin of the tool joint, longitudinally extending blades secured to the outer surface of the sleeve and

extending therebelow, the ends of the blades being extended beneath the lower end of the sleeve, the sleeve having a longitudinal port connecting said box with the lower end of the sleeve immediately in advance of the front face of each of said reamer blades.

4. In combination with a drill pipe including a tool joint disposed of above the lower end thereof and having a pin, a reamer comprising a sleeve surrounding the drill pipe, and having a box at its upper end for engagement with the pin of the tool joint, longitudinally extending blades secured to the outer surface of the sleeve and extending therebelow, the ends of the blades being extended beneath the lower end of the sleeve, the sleeve having a longitudinal port connecting said box with the lower end of the sleeve immediately in advance of the front face of each of said reamer blades, and other ports connecting said box with the outer surface of the sleeve adjacent the upper ends of said reamer blades.

5. In well drilling apparatus and in combination, a tool joint having a double pin at its lower end, a drill joint engaging the smaller pin of the tool joint, a sleeve engaging the larger pin of the tool joint, a bit engaged with the lower end of the drill joint, and reamer blades formed on the outer surface of the sleeve, said drill joint being provided with a wrench square spaced from the upper end thereof a distance greater than the length of said sleeve.

In testimony whereof I hereunto affix my signature.

NELSON S. BURTON.
